(57) **CLAIM**

We claim the ornamental design for a pet water fountain, as shown and described.

DESCRIPTION

FIG. 1 is a front, right and top perspective view of a pet water fountain according to a first embodiment of our new design;

FIG. 2 is a rear, left, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a circled portion 9 of FIG. 1; FIG. 10 is a front, right and top perspective view of a pet water fountain according to a second embodiment of our new design;

FIG. 11 is a rear, left and bottom perspective view thereof;

FIG. 12 is a front perspective view of the main body;

FIG. 13 is a rear perspective view thereof;

FIG. 14 is a left side view thereof;

FIG. 15 is a right side view thereof;

FIG. 16 is a top view thereof;

FIG. 17 is a bottom view thereof; and,

FIG. 18 is an enlarged view of a circled portion 18 of FIG.

10.

The broken lines depict portions of the pet water fountain in which the design is embodied that form no part of the claimed design.
